UNITED STATES PATENT OFFICE.

CASS L. KENNICOTT, OF CHICAGO, ILLINOIS, ASSIGNOR TO KENNICOTT WATER SOFTENER COMPANY, A CORPORATION OF ILLINOIS.

WATER-PURIFYING APPARATUS.

SPECIFICATION forming part of Letters Patent No. 767,698, dated August 16, 1904.

Application filed December 5, 1903. Serial No. 183,864. (No model.)

To all whom it may concern:

Be it known that I, CASS L. KENNICOTT, a citizen of the United States, residing at Chicago, in the county of Cook and State of Illinois, have invented a new and useful Improvement in Water-Purifying Apparatus, of which the following is a specification.

My invention relates particularly to water-purifying apparatus of the character disclosed in Letters Patent No. 665,606, granted to me January 8, 1901.

My primary object is to provide a substitute for the swinging pipe-section employed in connection with the float mechanism of said patented construction, the new construction possessing certain advantageous features, such as simplicity of construction and compactness. Incidentally it will be noted that in the new construction variation in the head of pressure at the discharge-orifice of the "hard-water" tank (supplying the water-wheel) is accompanied by variation in the area of the discharge-orifice of the chemical-solution (such as solution of soda) tank.

My invention is illustrated in the accompanying drawings, in which—

Figure 1 represents a broken vertical sectional view of water-purifying apparatus embodying my invention; Fig. 2, a broken bottom plan view of the chemical (soda) solution tank employed; and Fig. 3 an enlarged sectional view taken, as indicated, at line 3 of Fig. 2.

In the preferred construction, A represents a mixing-chamber located in the downtake-conduit A' of water-purifying apparatus of well-known general construction; B, a motor-casing surmounting the mixing-chamber; B', a water-wheel in said casing; B², a stirrer operated from the water-wheel; C, a hard-water tank provided with a discharge-spout a; C', a supply-pipe connected with a hydrant, (not shown;) D, a chemical-solution (preferably solution of soda) tank provided in its bottom with a discharge-orifice b; D', a source of supply for the tank D, from which source liquid is admitted automatically to the tank D by a float-controlled valve D²; D³, a conduit leading from the tank D to the mixing-chamber;

E, a horizontally-disposed slide or gate controlling the orifice b; E', a weight attached by a cord c to one end of said gate, said cord passing over a pulley c' in substantial alignment with the slide, and E² a float operated by water in the tank C and connected by a cord c² with the adjacent end of the slide E, the cord c² passing about a pulley c³ in substantial alignment with the slide.

The orifice b comprises a slot having converging sides, the large end of the slot being toward the pulley c³. The slide is reciprocable in guides d, extending longitudinally of the slot b. The conduit D³ has an enlarged admission end f, located beneath the slot b.

In operation water to be purified is contained in varying depth in the tank C, lime-water wells up into the mixing-chamber in a well-understood manner, and the tank D is supplied with chemical solution at a constant level. The water-wheel which serves to operate the stirrers and to supply any other necessary power is operated by the water entering the machine from the tank C. The quantity of hard water entering the machine, passing the wheel, and entering the mixing-chamber varies with a variation of the head of water in the tank C. As the slide E is connected with the float E² the slide is drawn to the right, decreasing the orifice b as the float descends, and the slide is drawn to the left by the weight E', increasing the size of the orifice as the float E² ascends. Thus it follows that as the discharge of hard water from the tank C increases the discharge of chemical solution from the tank D increases. Since the flow from the orifice a does not increase in direct proportion with the increase of head in the tank C, it is desirable that the orifice b shall not increase in size in direct proportion with the movement of the slide. Hence the reason for tapering the slot b. It is a simple matter to properly design the opening b to secure always the proper ratio between the hard-water and chemical solution entering the mixing-chamber.

From the foregoing explanation it will be understood that the ratio between the hard water and chemical solution entering the mix-

ing-chamber is preserved solely by a variation of the area of the discharge-orifice of the chemical-solution tank approximately with the variation in the head of water in the hard-
5 water tank. Obviously minor details of construction within the spirit of my invention may be made.

What I regard as new, and desire to secure by Letters Patent, is—

- 10 1. In apparatus of the character described, having a mixing-chamber, a water-supply tank having a discharge thereinto, a liquid-supply tank having in its bottom an elongated discharge-orifice communicating with said mixing-chamber, and a float operated with a variation in the height of water in said water-supply tank, a float-actuated horizontally-movable slide having a guide extending longitudinally with reference to said elongated orifice, for automatically varying the size of said discharge-orifice with a variation in the head in said water-supply tank, for the purpose set forth.
- 15 2. In apparatus of the character described, having a mixing-chamber, a water-supply tank having a discharge thereinto, a liquid-supply tank having a discharge-orifice communicating with said mixing-chamber, and a float operated with change in level in said
- 20 first-named tank, means for automatically varying the size of said discharge-orifice with a variation in the head in said water-supply tank, including a float-actuated slide control-

ling said discharge-opening, the discharge-orifice of the second-named tank tapering to 35 insure the proper proportionate discharge, for the purpose set forth.

3. In apparatus of the character described, having a mixing-chamber, a hard-water-supply tank, and a liquid-supply tank, in combination with means for varying the effective discharge-orifice of said second-named tank, comprising a horizontal discharge-orifice for said second-named tank, a horizontal gate therefor, potential means for moving said gate 40 in one direction, and a float actuated with change of level in the first-named tank and serving to actuate said gate in the other direction.

4. In apparatus of the character described, having a mixing-chamber, a hard-water-supply tank, and a liquid-supply tank, and means for varying the effective discharge-orifice of said second-named tank, comprising an elongated discharge-orifice in the bottom of said 55 second-named tank, a gate controlling the same and movable longitudinally thereof, a weight serving to actuate said gate in one direction, and a float in said first-named tank serving to actuate said gate in the other direction, for 60 the purpose set forth.

CASS L. KENNICOTT.

In presence of—

M. S. MACKENZIE,
WALTER N. WINBERG.
